UNITED STATES PATENT OFFICE.

JACOB H. COFFMAN, OF PHILADELPHIA, PENNSYLVANIA, ASSIGNOR OF ONE-HALF TO THOMAS OTT, OF PHILADELPHIA, PENNSYLVANIA.

DOOR STOP AND SECURER.

SPECIFICATION forming part of Letters Patent No. 731,342, dated June 16, 1903.

Application filed March 7, 1903. Serial No. 146,708. (No model.)

To all whom it may concern:

Be it known that I, JACOB H. COFFMAN, a citizen of the United States, residing at Philadelphia, in the State of Pennsylvania, have invented a new and useful Door Stop and Securer, of which the following is a specification.

This invention is a combined door stop and securer, the object being to provide a simple and efficient device which will serve to stop the door from striking the wall and also secure the same in such position, thereby holding it in an open position.

Another object is to provide a securer in combination with a stop, which securer can be quickly and easily released whenever it is desired to close the door.

With these objects in view the invention consists in providing a stop with a spring-securer which has an upwardly-extending free end having a shoulder adjacent said free end and in providing a spring-catch to be attached to a door, said catch having a central horizontal portion which is intended to engage the shoulder portion of the spring-securer carried by the stop.

The invention consists also in the details of construction and arrangement of parts hereinafter fully described, and pointed out in the claims.

In the drawings forming part of this specification, Figure 1 is a perspective view showing the practical application of my invention. Fig. 2 is a view showing the combined stop and securer in elevation, the door being held in contact with the stop by means of the securer. Fig. 3 is a top plan view of the stop and spring member connected thereto. Fig. 4 is a detail perspective view of the catch carried by the door. Fig. 5 is a detail perspective view of the spring member carried by the stop.

In carrying out my invention I employ an ordinary wooden stop-knob A, which is screwed into the chair-board A' in such position that when the door is completely opened it will contact with the said stop and will be prevented from striking the wall, and in practice I prefer to provide the stop with a rubber tip A², against which the door strikes. This stop A has a spring securing member B

connected thereto, said member being formed from a single piece of stout spring-wire which is coiled one or more times intermediate its ends, as shown at B', one end of the wire being bent down, as shown at B², which downwardly-bent end is inserted in a socket formed in the neck of the stop, as most clearly shown in Fig. 2. The other end of the wire is bent in an upward direction, as shown at B³, then downwardly for a short distance, as indicated at B⁴, the free end extending upwardly, as shown at B⁵, and it will be noted that both portions of the wire are substantially parallel, as indicated in Fig. 3, and that portion of the wire between the coil B' and the bend B² preferably rests in a longitudinal groove A³, produced in the broad face of the stop, thereby holding the securer in its proper position.

A spring-catch C is attached to the door D, adjacent to the point which contacts with the stop, said catch being adapted to engage the spring-securer attached to a stop, and in practice I prefer to construct the said catch from a single piece of stout spring-wire comprising the central horizontal portion C', parallel horizontal portions C², a spring-coil C³, from which depends the end portion C⁴, terminating in an eye C⁵, through which a screw is passed for the purpose of connecting the catch to the face of the door. The opposite parallel portion C² terminates in a point C⁶, which is driven into the door, thus preventing the catch from turning. A notch A⁴ is cut in one side of the stop at the inner end of the same, and through which is driven a nail A⁵ into the chair-board, said nail being intended to hold the knob or stop securely against rotation. The stop and securer connected therewith will consequently always be held in the proper position for the engagement of the catch carried by the door. When the door is thrown back, so that it contacts with the stop the central horizontal member C' rides upon the upwardly-inclined portion B³ and drops back of the downwardly-inclined portion B⁴, as most clearly shown in Fig. 2, thus securely holding the door against the stop, and when it is desired to disengage the door the catch can be disconnected from the securer by giving the door a quick jerk,

or the free end B^5 may be depressed sufficiently to clear the shouldered portion B^4 from the horizontal member of the catch.

Having thus fully described my invention, what I claim as new, and desire to secure by Letters Patent, is—

1. A combined door stop and securer comprising a stop adapted to be connected to a chair-board, a spring-securer attached to the said stop, said securer having an upwardly-extending free end provided with a shoulder adjacent to said free end, and a spring-catch adapted to be attached to the door and having a central horizontal member adapted to engage the shouldered portion of the spring-securer, as set forth.
2. A combined door stop and securer comprising a stop having a groove in the upper

face thereof, and a socket in the neck of said stop, a spring securing member formed of a single piece of wire and comprising the intermediate coil, the downwardly-extending end, the upwardly-inclined free end having the shoulder adjacent thereto, and the spring-catch adapted to be secured to the door and formed of a single piece of wire and comprising the central horizontal member, the parallel side members, the coil, the downwardly-extending end portion terminating in an eye, and the pointed extended end of the other parallel member as set forth.

JACOB H. COFFMAN.
